FLUID-DRIVEN PUMP CONTROL

Christopher A. Schellens, Tenants Harbor, Maine,
and Arthur L. Sherman, Englewood, N. J.

Application December 2, 1943, Serial No. 512,584

23 Claims. (Cl. 103—19)

1

This invention relates to improvements in control mechanism for high speed turbine-driven centrifugal pumps suitable for supplying feed water to boilers, and more particularly to such mechanisms designed to prevent over-speeding of the turbine-pump unit when the load on the turbine becomes insufficient to keep the speed down within safe limits, as when there may be a failure or throttling of the water supply to the pump, or when the water supplied to the pump becomes heated to such a high temperature that its suction head is insufficient to supply the demands of the pump without flashing to steam.

A primary difficulty encountered in connection with mechanisms for preventing over-speeding of turbine-driven pumps results from the tendency of control valves and operating parts to become stuck and rendered inoperative by formation of scale thereon, corrosion, etc. Such over-speed protective mechanisms may not be called upon to operate for long periods of time, and hence there is ample opportunity for scale to form and oxidization to occur unless effective measures are taken to prevent it. This tendency of control devices to become stuck and inoperative is particularly prevalent when the control is of a turbine-pump unit supplying feed water to boilers where hard or unclean water has to be used, and the pump unit may not be given requisite attention.

In Patent No. 1,725,722, granted August 20, 1929, to Christopher A. Schellens, one of the present joint applicants, there is disclosed an over-speed protective control which avoids much of the difficulty resulting from scaling and corroding of operating parts and which operates on the principle of effecting such control by inter-action of turbine steam pressure and pump-discharge pressure on the control valve, whereby the occurrence of a condition favorable to over-speeding of the pump unit results in a slowing down of the unit to a safe speed without an actual stopping of the unit, and the speed automatically is restored to normal when the faulty condition has been corrected.

Our present invention utilizes the same principle of automatic control of a turbine-driven pump against over-speeding by the opposed action of turbine steam pressure and pump delivery pressure on a control valve unit, and has among its objects to provide an improved control valve unit and improved means for effecting the control. In the illustrated embodiment of the invention, we provide a double-disc valve unit having an integral piston on which the turbine steam pressure acts in direction to close the valve discs

which the pump discharge pressure acts in the opposite direction tending to maintain the valve discs open. The water pressure may act through a lever, and an adjustable spring may act with the water pressure in opposition to the steam nozzle pressure and may be adjusted to hold the valve slightly open, even though the water pressure fails completely, so that the turbine can operate at a suitably low and safe speed until the water pressure is restored.

Another and important object of our present invention is to provide means for controlling the main control valve unit by controlling a relatively small flow of fluid whose pressure is effective on the main control valve unit. In some cases, this relatively small flow of fluid which is to be controlled may be steam which escapes past a steam piston on the control valve unit and which is conducted through a relatively small pipe to the exhaust side of the turbine, the control of which can maintain a constant or nearly constant pump discharge pressure at the pump outlet notwithstanding variations in the volume of liquid discharged; or, as herein shown, the control may be of a small flow of liquid in a relatively small pipe which leads from the discharge side of the pump to the under side of a water piston acting in opposition to the steam nozzle pressure on the control valve unit; or under some conditions, it may be desirable to effect the control by controlling a relatively small flow of liquid which has leaked past the water piston into a conduit leading to the suction side of the pump. Furthermore, the valve or other means for controlling the small flow can be small and, if desired, may be placed at a remote location where it can provide sensitive and inexpensive control by hand or automatically, such as by a float operating in the feed tank which supplies the pump, or other well known control devices which respond to water level, pressure, temperature, or other characteristics which it is desired to control.

A further object is to combine with the above mentioned control of over-speeding by the relation of steam pressure to water pressure, a centrifugal acting trip control for stopping pump operation in the event of over-speeding of the turbine-pump unit. Associated with a lever through which the water pressure acts on the piston of the control valve unit, we provide trip mechanism operative in response to speeding up of the pump shaft, for removing the force due to the upward pressure on the piston of the valve unit so that steam pressure can completely close the valves 55 against admission of steam to the turbine. The

provision for this emergency shut-down control and the structure for causing its action through the same valve unit that controls normal operation and emergency slow-down operation of the turbine-pump unit constitute additional objects of our invention.

Another object resides in provision for conducting steam leaking past the steam pressure control piston to the exhaust side of the turbine, and for conducting water leaking past the water pressure control piston to the suction side of the pump, thereby providing conduit connections whereby pump inlet pressure and turbine exhaust pressure are constantly acting on the control valve which responds to variations in these pressures to compensate therefor and ensure a proper positioning of the valve unit under all conditions of operation.

Still another object of the invention is to provide means for maintaining a proper equilibrium of the control valves in the event of a drop in steam pressure. It has been customary heretofore to provide a valved conduit whereby one or more auxiliary nozzles might be thrown into communication with the normally operating nozzle belt of the turbine when the steam supply pressure drops, thereby to prevent a drop in pump delivery pressure and volume under conditions of nearly full load. With our improved control valve unit, such a cutting-in of one or more extra or auxiliary nozzles would disturb the equilibrium relations between bowl pressure and delivery pressure acting respectively on the steam and water pistons unless means were provided for correcting this effect. Such means is provided in the form of a conduit connecting the auxiliary nozzle belt to a chamber in the control valve casing whereby the auxiliary nozzle pressure acts with and in addition to the normally operating nozzle pressure when the said valved conduit of the auxiliary nozzle or nozzles is open.

It is, moreover, our purpose and object generally to improve the structure and operation of over-speed controls for turbine-driven centrifugal pumps.

In the accompanying drawings:

Figure 1 is a diagrammatic view showing a turbine-driven pump and control system, embodying features of our invention, for supplying feed water to a boiler, the control unit being shown separated and turned around relative to the turbine-pump unit, and the centrifugal trip mechanism being omitted.

Figure 2 is a vertical cross-sectional view showing our improved control mechanism in its relation to the shaft of the turbine-pump unit;

Figure 3 is a view looking from the left in Figure 2, the upper portion being in vertical cross-section on line 3-3 of Figure 2;

Figure 4 is a cross-sectional view on line 4-4 of Figure 2;

Figure 5 is a perspective of the centrifugal trip mechanism shown in elevation in Figures 2 and 3;

Figure 6 is a detail cross-sectional view approximately on line 6-6 of Figure 5, showing a means for adjusting the latch; and

Figure 7 is a fragmentary elevation showing the hand valve, conduit, and connections for applying the steam pressure of the auxiliary nozzles to the upper end of the valve unit.

Referring to the drawings, and more particularly to Fig. 1, the present invention is shown applied to a feed-water pump 10 which draws feed-water through pipe 12 from a suitable source, such as the tank 14, and delivers it through a

combined check and regulating valve 16 to the boiler 18 after first passing the water through a heater 20 connected in the delivery pipe 22. A shut-off valve 24 is provided in the suction pipe 12 and the delivery pipe 22 has a check-valve 26 located between the pump and heater 20, and has a pressure relief valve 28 between the pump and check-valve 26, with relief conduit 30 opening into the tank 14.

10 Pump 10 is a turbine-driven high speed centrifugal pump whose turbine 32 is supplied with steam through pipe 34 leading from any suitable source of steam, the exhaust from the turbine being conducted through pipe 36, having the usual shut-off valve 38, to any convenient exhaust steam conduit or chamber.

Control mechanism embodying features of the invention is arranged in the steam line 34 between the steam source and the turbine. As illustrated in the drawings, the control mechanism is mounted on the turbine casing, as best seen in Fig. 3, and comprises a valve casing 42 secured to the top of the turbine casing as by the screws 44. An entrance chamber 46 within valve casing 42 has the steam pipe 34 delivering thereto, and a discharge chamber 48 of the valve casing opens directly into the turbine.

The amount of steam admitted to the turbine is controlled within the valve casing 42 by a 30 double-disc valve unit whose discs 50, 52 respectively control the ports 54, 56 in the walls 58, 60 which constitute partition walls between the entrance and discharge chambers 46, 48 of the valve casing 42. The discs are mounted in fixed spaced 35 relation on a valve stem 62 whose upper end is slidably mounted as at 64 and whose lower end is formed as a piston or plug 66 which is slidable in the cylindrical passage 68 in wall 70. Passage 68 leads between discharge chamber 48 and a shallow chamber 72 but is continually closed by the 40 slidable piston or plug 66 excepting as slight leakage of steam past the piston into chamber 72 may occur and be conducted through pipe 74 to the turbine exhaust pipe 36, or exhaust chamber 45 of the turbine casing.

From the foregoing description, it will be obvious that the pressure in discharge chamber 48 of valve casing 42 corresponds to the turbine nozzle bowl pressure and continually acts on the 50 piston 66 tending to force it downward to a valve-closing position. According to the invention, however, any downward movement of the piston is resisted by mechanism which is responsive to the water pressure at the delivery side of the pump, so that the positions of valve discs 50, 52 at any time during operation of the pump is determined by the existing turbine nozzle bowl 55 pressure and the water pressure on the delivery side of the pump. Figs. 2, 3 and 4 show mechanism for thus controlling valve discs 50, 52. In Figs. 2 and 3, a bracket 76 is mounted on the under side of valve casing 42 at the part thereof which projects from the turbine casing, as best seen in Fig. 3. Operable in the bracket 76 is a lever 78 whose one end is pivoted at 80 to the upper end of a link 82 of centrifugal trip mechanism later to be described, and whose other end has a knife-blade bearing on a vertical rod 86 which extends slidably entirely through bracket 76 with a coil spring 88 surrounding the upper part of the rod and under compression between the bracket 76 and a disc 90 which is adjustable to vary the spring tension by means of nut 92 on the threaded upper end of rod 86. As shown 70 in Fig. 2, the knife-blade bearing of lever 78 on

rod 86 is attained by having the rod extend through a relatively large hole 92 in the end of the lever, within which hole is fixedly mounted a bushing 94 having V-notches on opposite sides of rod 86 which engage knife-edges on a loose bushing 96 which in turn has a similar knife-edge bearing at 84 on a collar 100 fixed on rod 86. Hence spring 88 constantly tends to raise or lift rod 86 and the end of lever 78 through which the rod extends.

This lifting tendency of spring 88 is resisted by the steam pressure acting on piston 66 and through a rod 102 on the lever 78. Rod 102 extends vertically through a relatively large hole 104 at a mid-location along lever 78 and through the upper wall of bracket 76 and the under wall of valve casing 42 into the shallow chamber 72, with the upper end of rod 102 engaging the lower end of piston 66. Rod 102 has a knife-blade bearing on the lever 78, the rod having a fixed collar 106 with knife-edges and the lever having a rigid sleeve 108 with V-notches in which the knife-edges of collar 106 engage as at 109 in Fig. 2. A shield 110 on rod 102 covers the hole 104 through the lever against foreign matter and drip getting into the knife-edge bearing. The lower end of rod 102 extends into a dash pot 112 and is equipped with a disc-like piston 114 for braking and preventing fluttering of rod 102. Hence spring 88 continually acts to maintain the upper end of rod 102 pressed tightly against the lower end of piston 66.

Referring to Fig. 2, the rod 86 at the end of lever 78 has its lower end projecting into a casing 116 secured on the under wall of bracket 76. This casing 116 interiorly is divided by wall 118 into upper and lower chambers 120, 122, and a piston or plug 124 is vertically slidable in a short cylinder 126 in wall 118 with its upper end arranged in position to engage the lower end of rod 86. Upper chamber 120 of casing 116 is connected through pipe 128 to the suction side of the pump, and lower chamber 122 is connected by the relatively small diameter pipe 130 to the pressure or discharge side of the pump. Hence the lower end of piston 124 which is in chamber 122 is subjected to pump discharge pressure which acts upward on the piston tending to raise rod 86 and the end of lever 78. However, the turbine nozzle bowl steam pressure is acting downward on the steam piston 66 and through rod 102 resists upward movement of lever 78 by the water pressure, so that the position of steam piston 66 and thus of valve discs 50, 52 is determined by the relation of steam pressure to the water pressure. So long as the water pressure in conjunction with spring 88 can overcome the steam pressure acting downward on piston 66, the valve discs 50, 52 will remain open more or less depending upon the relation of the opposing pressures. However, if tank 14 should run dry, or the water supply to the pump fail or become inadequate for some other reason, the resulting sudden drop in pump discharge pressure is communicated through pipe 130 to the under side of water piston 124 and the steam pressure then can force this water piston 124 downward until the valve discs 50, 52 become closed or nearly closed, to stop or slow down the turbine. Preferably the spring 88 will be adjusted initially so that the turbine will continue operation at an idling speed even though the water supply to the pump fails, this turbine idling speed being such that no harm can result even though the supply water for the pump be completely cut off. Then when the water pressure

builds up again, as by replenishing the supply in tank 14, or by correcting some other faulty condition, the water piston 124 will be forced upward to open valve discs 50, 52 gradually until they are again open and a normal operating condition is restored.

It is a feature of importance that operation of valve discs 50, 52 can be controlled by controlling the water flow in the small pipe 130. In this connection it is notable that flow in pipe 130 is limited to the leakage past the water piston 124 and is relatively small. Piston 124 is slightly less in diameter than the interior diameter of its cylinder 126 so that this slight leakage past the piston can occur from lower chamber 122 to upper chamber 120, whence the leakage water passes through pipe 128 to the inlet or suction side of pump 10. We have found that by controlling the small flow in pipe 130 the water pressure on water piston 124 can be modulated to control the valve discs 50, 52. For this purpose, we show in Figs. 2 and 4 automatic valve mechanism associated with casing 116 although the control might be by manual or automatic means anywhere in the extent of pipe 130 which, because of its small size, can extend, if desired, to a location remote from the pump and the control means be located at the remote point. A mere hand operated valve in pipe 130 can accomplish this control, or a well known type of float controlled valve operated by a float in the tank 14 could be employed for controlling flow in pipe 130. As represented in the drawings, an automatic valve responsive to and holding substantially constant the pump delivery pressure accomplishes the said control of flow in pipe 130. Valve spindle 132 is vertically movable in a fixed valve sleeve 136 which has ports 138 through its walls opening into the lower chamber 122 of casing 116 and ports 140 opening into the upper chamber 120. The lower end of sleeve 136 has the oppositely disposed V-notches 142 in its walls through which water from pipe 130 can pass into sleeve 136 and thence through ports 138 to chamber 122 when the valve spindle is in its lowermost position of Fig. 2, the valve spindle 132 having a reduced part 133 for this purpose. The upper end of valve spindle 132 is connected as at 144 to an inverted flanged cup member 146 in the cylindrical part 148 integral with casing 116, the member 146 being yieldably held in its lowermost position of Fig. 2 by a coil spring 150 which is under compression between the flange of member 146 and the flange of an upright flanged cup member 152 which is adjustable to vary the compression of the spring, as by the adjusting screw 154 threaded in a depending part of a removable cover plate 156 on cylinder 148.

When valve spindle 132 is in its lowermost position of Fig. 2, water from pipe 130 enters lower chamber 122 as previously described and pump outlet or delivery pressure is thereby communicated to the under side of water piston 124. However, this water pressure in the small chamber 126 below the valve spindle 132 acts on the lower end of the valve spindle as a piston and, under normal operating conditions, will force the valve spindle upward against the pressure of spring 150, with gradual reduction of the flow passages through the V-notches 142.

The throttling of the flow through the said V-notches results in the reduction of the pressure on the under side of piston 124 to a point where the steam piston 66 starts to close the steam valve discs 50, 52 and thereby reduces the input to the turbine. This results in a reduced de-

livery pressure with the consequent reduction of the upward force on valve spindle 132 until this force is in equilibrium with the spring force. Consequently whatever the volume of water pumped the above described mechanism will operate to maintain that delivery pressure which is predetermined by the adjustment of the tension on spring 150.

In many pumping systems, and in particular in the feeding of boilers, there is a constantly fluctuating demand for water which necessitates some operative control means for the steam input. This means is constantly in motion as the load fluctuates. The control may be manual or automatic, responsive to water level, speed, pressure, temperature or other physical qualities, and if, as is contemplated in our invention, this control acts through the throttling of the flow through pipe 130, it will be seen that the steam valve spindle 62 will be kept in constant fluctuation, and never can become scaled or stuck and, since this same structure acts for the emergency controls, it is constantly in readiness to function effectively and efficiently in any emergency. In contrast, the prior controls which require separate valves in the steam line to the turbine respectively for normal operating control and for emergency control, are not satisfactory because the emergency control may not be called into action for long periods of time and the emergency control valve and operating mechanism is subject to scaling and corrosion so that they cannot function in emergencies and serious damage frequently results. Such a failure cannot occur with our present control system and, if the steam valve discs 50, 52 should become scaled and stuck due to some very bad water, the condition would be detected immediately at the control location by a departure from its normal value of whatever physical quantity is being held constant such as pressure, for example, and the operator or attendant could correct the condition by manually activating lever 78 to free valve discs 50, 52.

Associated with automatic valve 132 is a hand controlled shut-off valve 134 (Fig. 4) which normally is closed when the system is operating under the control of automatic valve 132. The hand valve 134 controls flow in a by-pass 160 which extends between the small chamber 158 below valve 132 and through the ports 138 and reduced part 133 of valve 132 into chamber 122. As previously stated, hand valve 134 normally is closed so that the water flow into chamber 122 is through the V-notches 142. When it is desired to render automatic valve 132 inoperative, hand valve 134 is opened to by-pass the water flow. The resulting increased flow acting on water piston 124 produces increase of the pump delivery pressure which, acting on the lower end of valve 132, forces the valve upward to close the V-notches 142. Control of the system then must be accomplished by other means, such as by the hand wheel 162.

To start the pump in operation, the hand wheel 162 is turned to back its stem 164 away from the upper end of the valve stem 62 of the steam valve discs 50, 52. This hand wheel and stem 162, 164 constitute a means for manual closing of valve discs 50, 52 to stop turbine and pump operation. If the steam line 34 is open when valve discs 50, 52 are thus freed, spring 88, acting through lever 78 will open valve discs 50, 52 an amount to permit turbine operation at a speed corresponding to a safe idling speed. Assuming a free and adequate flow of water to the pump, the pump will

operate at slow speed, gradually building up a water pressure which acts on water piston 124 to gradually open the steam valve discs 50, 52 more and more, increasing the steam input to the turbine 5 which hastens the rise in water pressure and ultimate normal opening of valve discs 50, 52. Spring 58 initially is adjusted so that in absence of any water pressure on piston 124, it will maintain valve discs 50, 52 open a slight amount 10 so that the turbine can operate at a safe starting or idling speed. Each individual pump unit has a definite bowl pressure at which it will idle safely and, by setting the spring tension to equilibrate the lever system when piston 66 is subjected to this particular pressure with no pressure on the water piston, discs 50, 52 will automatically be brought to such a position of throttling as to secure this bowl pressure. If, as is preferred, the spring has a flat characteristic this idling bowl 20 pressure will not vary substantially even though the pressure of the steam supply varies greatly. Once spring 58 has been thus properly adjusted, it needs no further attention. Hence, so long as steam line 34 is open, steam can enter the turbine 25 and cause its operation at a speed slow enough to be safe even though no water is being delivered by the pump. Our invention therefor provides the important advantage that a water supply failure for any cause does not result in shut-down of the turbine and pump but only slows the turbine to a safe idling speed from which it can gradually build up normal speed when the pump again receives and delivers water in a normal manner without the attention of an attendant. 30

35 The prior controls acting to shut down the pump have the disadvantage that the whole plant may

have to be shut down until a water failure situation is corrected and the control mechanism manually reset. Our present mechanism acts

40 in an emergency to prevent over-speeding and, when the emergency condition is corrected, restores the system to normal without attention.

The mentioned reduction of the speed of the turbine and pump due to a water failure ordinarily is to a safe speed which cannot build up to an over-speeding condition capable of harmful effects. It may happen, however, under unusual conditions where the safe speed margin is small, that a slight over-speeding might occur. Hence, we provide a further safety control actuated by a centrifugal trip mechanism associated with the pump shaft 163. A collar or sleeve 169 is slidably keyed on shaft 163 in association with any suitable centrifugally acting means for actuating it in axial direction, such as the centrifugal mechanism disclosed in Patent No. 2,124,339, granted July 19, 1938, to Christopher A. Schellens, one of the present joint applicants. An arm 170 is fixed on the inner end of a short shaft 172 suitably mounted for free rotation in the side wall of the turbine-pump casing. As illustrated in Fig. 2, an opening 174 is provided in the casing wall and is closed by a cover plate 175 in which shaft 172 is journaled as at 45 173. On the outer end of shaft 172 is fixed a latch member 183 whose depending part 182 has a projecting lug 184. Mounted on cover plate 176 is a pair of brackets 178a in which is pivotally mounted at 187 the lever arm 188 having a forked upper end pivotally connected at 190 to the lower end of the link 82 to whose other end is pivotally connected at 89 the steam valve operating lever 78. Preferably lever arm 188 has a depending tail part 189 for engaging a shock-absorbing mechanism or buffer 192 when

the centrifugal trip operates. Rigid with lever arm 183, or mounted to move in unison therewith, is a member 194 having a pin 196 normally engaging under projecting lug 184 of latch member 180. A coil spring 193 is connected at one end to the upstanding part 181 of latch member 180, as at 200, and has its other end connected to member 194 by means of a pin 202. Hence the spring constantly biases member 194 in counter-clockwise direction as viewed in Fig. 2, and latch lug 184 normally restrains such movement. However, if the turbine shaft 166 should speed up to an unsafe speed for pump operation, the centrifugal acting mechanism (not shown) on shaft 166 moves collar 163 into contact with arm 178 and rocks the latch member 180 counter-clockwise in Fig. 5, thereby releasing the latch and permitting spring 193 to rotate member 194 and lever arm 188 counter-clockwise in Fig. 2, thereby to pull down on lever 18 which leaves the control valve discs 50, 52 free to be completely closed by the steam pressure, to stop the turbine and pump. Preferably a cam 195 is provided on member 194 to hold arm 178 out of engagement with sleeve 163 to avoid undue wear of the point of engagement when the trip mechanism operates.

Provision is made for adjustment of the setting of latch member 180, as shown in Fig. 6. By mounting latch member 180 on the enlarged cylindrical part 187 on shaft 172, the heads of the bolts 183, 185 can seat in notches 188 on opposite sides of cylinder 187 so that, by loosening one bolt and tightening the other, any needed adjustment of latch member 180 conveniently may be effected.

A further feature of our invention resides in provision of means for cutting in one or more auxiliary steam nozzles and simultaneously increasing the effective area upon which the steam pressure acts tending to drive steam piston 66 downward if the steam pressure in the turbine supply line drops. By this means we can maintain the turbine power approximately as it was prior to the pressure drop without changing the equilibrium of the control system, so that the pump continues normal operation during the adverse steam condition without its safety against over-speeding being reduced. Referring to Fig. 7, a hand valve 204 controls a steam conduit 205 for cutting in the auxiliary nozzle or nozzles in the auxiliary nozzle belt 207, and a conduit 208 leads between conduit 205 and the chamber 208 in bonnet 210 of the main valve casing 42. The upper end of valve stem 20 is in this chamber 208 so that when the manual control stem 164 is backed away as in Fig. 2, the top of stem 62 is subjected solely to whatever pressure exists in chamber 208 and is added to the area of piston 66 upon which steam pressure is acting downward on the valve unit. Hence, at times of reduced steam pressure, opening of valve 204 opens chamber 208 to the steam pressure at the auxiliary nozzle bowls which acts downward on the end of valve stem 62, thereby to permit the reduced steam pressure to maintain equilibrium of the valve unit because acting on a larger area. When hand valve 204 is closed, the top of valve stem 62 similarly is subjected to exhaust pressure.

The relative sizes of steam piston 66 and water piston 124 are proportioned to suit the rated steam and water pressures and are such that at full rated delivery volume there is a slight excess upward force on the water piston tending to hold

the valve open, assuming that the regulator 132 is at its extreme lower position or the valve 134 is wide open. This upward bias increases if the delivery volume is decreased as by hand manipulation of the hand wheel 162 and its stem 164, the amount of increase depending upon the pump characteristics. Under these circumstances the opening of discs 50, 52 is determined by the position of stem 164. When the system is controlled by the throttling of the water supply to the under side of water piston 124, as by the operation of regulator 132, and the hand wheel stem 164 is in its upper position, the upward bias disappears since the forces acting on the lever 18 are in equilibrium at all delivery volumes. In the event of a failure of the water supply to the pump, however, the regulator 132 will call for more pressure and will open wide. Consequently from the standpoint of safety from over-speeding, the full delivery pressure may be regarded as acting on the under side of water piston 124. If the piston is made too large, the excessive upward bias at lighter delivery volumes would prevent the rapid closing of the valve to prevent over-speeding. Assuming that valve 134 is open, an unsafe upward bias would be produced by an excessive throttling of the discharge line, as at valve 16, except for the opening of relief valve 23 which relieves the discharge pressure and limits it to a safe value. This relief valve is therefore an important part of the system.

In the above analysis it has been assumed that the pump inlet and turbine exhaust pressures were nearly atmospheric as is the case in many installations, but a large departure from atmospheric of either of these pressures has a bearing on the operation of the valve. If, for example, the steam and water pistons were designed for a machine having a high exhaust pressure, the exhaust pressure may be considerably lower than its rated value at times. Under these conditions, at a given delivery volume and pressure, a lowered turbine bowl pressure would exist which would increase the upward bias on the valve system and render it unsafe for rapid closure in the event of water supply failure. This effect is compensated for if the chamber 72 is piped to the exhaust chamber of the turbine by lowering the pressure on the under side of the steam piston 66 and thereby restoring the bias to its safe value. A like effect results if the suction pressure is raised and compensation is secured by piping the upper chamber 120 to the suction side of the pump as heretofore described.

From the foregoing description, it will be apparent that we have provided mechanism which effectively controls a turbine-driven centrifugal pump, ensuring against over-speeding and against scaling and sticking of the control valves. Also it provides for preventing over-speeding without shutting down the pump but merely by slowing its operation to a speed which is safe even through no water is entering the pump; and the speed is automatically restored to normal when the pump again receives an adequate supply of water. However, a centrifugal trip control stands ever-ready to stop the pump if over-speeding should, for any reason, occur.

The control of the main steam valves by controlling the relatively small flow of water in a small pipe which can be remote from the pump is a definite and valuable advance over prior proposals and, in conjunction with the various other novel features described, provides a feed-water system which is more definite and sure

in operation than any previous system of which we have knowledge.

It will be apparent to those skilled in the art that the structure described herein is illustrative of but one of several methods which might be employed in practicing the invention for securing the desired relations of bowl, discharge, suction and exhaust pressures to the pump characteristics. The modulation of the forces motivating the discs 50, 52 can be accomplished by the throttling or bleeding of exhaust pressure or bowl pressure rather than by the throttling of the discharge pressure as described above. Furthermore, the lever structure shown merely is representative of one method of transmitting the relative pressures and securing the desired relations. An important feature of our invention resides in the discovery of the necessary functional relation of pressure, volume, speed in the accomplishment of the necessary results as set forth, and it is intended that the patent shall cover, by suitable expression in the appended claims, the broad aspects of the invention including whatever features of patentable novelty exist in the invention disclosed.

We claim as our invention:

1. Control mechanism for a turbine-driven pump comprising a valve unit controlling the supply line to the turbine, means for applying to the valve unit the turbine nozzle bowl pressure in direction tending to close the turbine supply line and the pump delivery pressure in direction tending to open the turbine supply line, and means for controlling the effect of the pump delivery pressure as applied to the valve unit, said valve unit comprising a pair of discs fixed in spaced relation on a valve stem and a piston rigid on one end of the stem, the unit as a whole being movable between a position in which said discs close the supply line to the turbine and positions in which the valves are open more or less depending upon the relation of the opposing pressures acting on the valve unit, and said means for controlling the effect of the pump delivery pressure comprising a member movable in response to pressure applied thereto and arranged to act on the piston of the valve unit, a relatively small conduit leading from the delivery side of the pump and applying the pump delivery pressure to said member in direction tending to open said discs, and means for controlling flow in said relatively small conduit.

2. Control mechanism for a turbine-driven pump comprising a valve unit controlling the supply line to the turbine, means including a piston rigid on the valve unit for applying to the valve unit the turbine nozzle bowl pressure in direction tending to close the supply line to the turbine, means including a piston for applying to the valve unit the pump delivery pressure in direction tending to open the supply line to the turbine, and conduits respectively for conducting fluid leaking past the first said piston to the exhaust side of the turbine and for conducting water leaking past the second said piston to the suction side of the pump.

3. Control mechanism for a turbine-driven pump comprising a valve unit controlling the supply line to the turbine, means for applying to the valve unit the turbine nozzle bowl pressure in direction tending to close the turbine supply line and the pump delivery pressure in direction tending to open the turbine supply line, means acting with and in addition to the pump delivery pressure on said valve unit for maintaining the

valve unit against complete closing by the turbine nozzle bowl pressure in absence of pump delivery pressure, thereby to reduce turbine operation to a safe idling speed without stoppage of the turbine, and automatic trip mechanism responsive to over-speeding of the turbine and operative to permit complete closing of said valve unit thereby to stop turbine operation.

4. Control mechanism for a turbine-driven pump comprising a valve unit controlling the supply line to the turbine, means for applying to the valve unit the turbine nozzle bowl pressure in direction tending to close the turbine supply line and the pump delivery pressure in direction tending to open the turbine supply line, said means for applying the pump delivery pressure to the valve unit including a lever arranged to act on said valve unit at a location intermediate of the ends of the lever, trip mechanism normally supporting one end of the lever and responsive to over-speeding of the turbine for releasing said end whereby the turbine nozzle bowl pressure can close said valve unit and stop the turbine, a relatively small conduit leading from the delivery side of the pump and applying the pump delivery pressure to the other end of said lever in direction tending to open the valve unit, and means acting on said other end of the lever with and in addition to the pump delivery pressure for preventing total closing of the valve unit in absence of pump delivery pressure and so long as said trip mechanism is in non-tripped condition.

5. Control mechanism for a turbine-driven pump comprising a valve unit controlling the supply line to the turbine, means for applying to the valve unit the turbine nozzle bowl pressure in direction tending to close the turbine supply line and the pump delivery pressure in direction tending to open the turbine supply line, said means for applying the pump delivery pressure to the valve unit including a lever pivotally mounted at one end, a rod flexibly connected to its other end with an adjustable spring acting on said rod and biasing it and its end of the lever in one direction, a relatively small conduit leading from the delivery side of the pump and applying pump delivery pressure to said rod in the direction of its spring bias, and means intermediate of the ends of the lever and carried by the lever engaging said valve unit and held thereagainst by the bias of said spring and by the pump delivery pressure, said spring bias being sufficient in absence of pump delivery pressure to maintain the valve unit slightly open against the turbine nozzle bowl pressure acting in direction to close it.

6. Control mechanism for a turbine-driven pump comprising a valve unit controlling the supply line to the turbine, means for applying to the valve unit the turbine nozzle bowl pressure in direction tending to close the turbine supply line and the pump delivery pressure in direction tending to open the turbine supply line, said means for applying the pump delivery pressure to the valve unit including a lever engaging the valve unit intermediate of the ends of the lever and pivotally mounted at one end, a rod flexibly connected to its other end, a relatively small conduit leading from the delivery side of the pump and applying pump delivery pressure to said rod in direction tending to hold the lever against the valve unit, and automatic valve means in said relatively small conduit responsive to fluctuations of pump delivery pressure for controlling flow in said conduit thereby to control the effect of the pump delivery pressure acting on said valve unit.

in opposition to the turbine nozzle bowl pressure.

7. A turbine-driven pump and control mechanism therefor comprising a turbine having a normally operative nozzle belt and an auxiliary nozzle belt, a valved conduit for cutting in said auxiliary nozzle belt, a control valve unit controlling the supply line to the turbine, means for applying to the control valve unit the turbine nozzle bowl pressure in direction tending to close the turbine supply line and the pump delivery pressure in direction tending to open the turbine supply line, and means for maintaining equilibrium of the valve unit when pressure in the turbine supply line drops and the valved conduit is opened comprising a conduit leading from said valved conduit on the exhaust side of the valve therein, and applying the auxiliary nozzle bowl pressure to the control valve unit in direction tending to close the turbine supply line and over an area of said control valve unit additional to the area on which the pressure of the normally operative turbine nozzles act on said control valve unit.

8. Control mechanism for a turbine-driven pump comprising a valve unit controlling the supply line to the turbine, means for applying to the valve unit the turbine nozzle bowl pressure in direction tending to close the valve unit, means for applying the pump delivery pressure to the valve unit in direction to open the valve unit, and adjustable means acting with and in addition to the pump delivery pressure on said valve unit in opposition to said turbine nozzle bowl pressure, said adjustable means being constructed, arranged and adjustable to maintain said valve unit slightly open even though the pump discharge pressure drops to zero, trip mechanism associated with said means for applying the pump delivery pressure to the valve unit, and centrifugally responsive means on the turbine shaft for tripping said trip mechanism upon over-speeding of the turbine thereby to stop the turbine.

9. Control mechanism for a turbine-driven pump comprising a valve-carrying piston having a pair of discs arranged and operative to control the supply line to the turbine, the turbine nozzle bowl pressure acting on said piston in direction to close the supply line to the turbine, a member operable on said piston in opposition to said turbine nozzle bowl pressure, a second piston for actuating said member, and means for applying the pump delivery pressure to the second said piston and through said member to the first mentioned piston in opposition to said turbine nozzle bowl pressure.

10. Control mechanism for a turbine-driven pump comprising a valve-carrying piston having a pair of discs arranged and operative to control the supply line to the turbine, the turbine nozzle bowl pressure acting on said piston in direction to close the supply line to the turbine, a lever having a part intermediate its ends operable on said piston in opposition to said turbine nozzle bowl pressure, trip mechanism normally supporting one end of the lever, means for applying the pump delivery pressure to the other end of the lever in direction urging said intermediate part of the lever toward said piston, means for varying the effect of the pump delivery pressure as applied to said lever thereby to alter the relation of turbine nozzle bowl pressure and pump delivery pressure in their cumulative effect on the positions of said discs, and means for tripping said trip mechanism in response to an over-speeding condition of the turbine, thereby to remove from the

piston the pressure in opposition to the turbine nozzle bowl pressure, whereby the latter pressure can close the discs and stop the turbine.

11. Control mechanism for a steam-turbine-driven pump comprising a source of steam and a conduit thence to the turbine, a source of water and a conduit thence to the pump, a valve unit in the steam conduit controlling the amount of steam delivered to the turbine, a pump delivery conduit having a pressure relief valve therein, means for applying turbine nozzle bowl pressure to said valve unit in direction tending to close the steam supply conduit, means for applying pump delivery pressure to the valve unit in opposition to the turbine nozzle bowl pressure, a spring acting with and in addition to the pump delivery pressure and adjustable to a tension capable of preventing total closing of the steam supply conduit by the turbine nozzle bowl pressure in absence of pump delivery pressure, whereby a failure of pump delivery pressure results in slowing down of the turbine, and means responsive to over-speeding of the turbine for stopping the turbine.

12. In a fluid driven pump, a valve unit controlling the supply of fluid for driving the pump, means for applying to the valve unit the pressure of the fluid leaving the valve unit in direction tending to close the valve unit, means for applying to the valve unit the pump delivery pressure in direction tending to open the valve unit, and mechanism in actuating relation to the valve unit and constantly engaging the valve unit, said mechanism including a spring biasing the mechanism into engagement with the valve unit in direction tending to open the valve unit, whereby said mechanism acts with and in addition to the pump delivery pressure to maintain said valve unit slightly open even though the pump delivery pressure drops to zero.

13. In a fluid driven pump, a valve unit controlling the supply of fluid for driving the pump, means responsive to increased pressure of the fluid leaving the valve unit to bias said unit towards closed position, means responsive to decreased exhaust pressure of the driving fluid to bias said unit towards closed position, means responsive to increased pump delivery pressure to bias the unit towards open position, means responsive to decreased pump inlet pressure to bias the unit towards open position, and means for regulating the pressure biasing one of said means, thereby to control the valve unit.

14. In a fluid driven pump, a valve unit controlling the supply of fluid for driving the pump, means for applying to the valve unit the pressure of the fluid leaving the valve unit, in direction tending to close the valve unit, means for applying to the valve unit the pump delivery pressure in direction and manner tending to open the valve unit, the latter pressure tendency being stronger than the former pressure tendency, whereby the valve tends towards wide open position when the said pump is operating normally and tends towards closed position when the pump delivery pressure is excessively reduced, and means for varying the opening tendency of said delivery pressure on said valve unit to effect positioning of the valve unit at such intermediate positions between fully open and fully closed positions as may be required to suit the load demands on said pump.

15. Control mechanism for a pump driven by a turbine having an auxiliary nozzle belt, comprising a valve unit controlling the supply line to the turbine, a conduit connecting the auxiliary

nozzle belt with the discharge side of the valve unit for supplying the auxiliary nozzle belt with driving fluid from the discharge side of said valve unit, a valve in said conduit for controlling the flow therethrough, means for applying to the valve unit the pressure of the driving fluid leaving said valve unit in direction tending to close the supply line, means acting with and in addition to the first said means for applying to the valve unit the auxiliary nozzle belt pressure in direction tending to close the supply line, and means for applying to the valve unit the pump discharge pressure in direction tending to open said supply line.

16. Control mechanism for a turbine-driven pump comprising a valve unit controlling the supply line to the turbine, means for applying to the valve unit the turbine nozzle bowl pressure in direction tending to close the valve unit, means for applying to the valve unit the pump delivery pressure in direction tending to open the valve unit, the latter said means including a chamber, and a relatively small conduit leading thereto from the discharge side of the pump, and means for reducing the said valve opening tendency including means permitting leakage from said chamber, and throttling means in said conduit.

17. Control mechanism for a turbine-driven pump including a valve casing for supplying driving fluid to the turbine, a valve unit including a disc movable in the casing and coacting therewith to control the amount of said driving fluid supplied to the turbine, means responsive to and increasing with the discharge pressure of said pump acting on said valve unit and tending to move said disc to open position, means within the valve casing responsive to the turbine bowl pressure acting on said valve unit and tending to move said disc to closed position, and adjustable means acting on the valve unit in opposition to said bowl pressure and adjustable to hold said disc in equilibrium when said discharge pressure is zero and when said bowl pressure is relatively small.

18. Control mechanism for a turbine-driven pump including a valve casing for supplying driving fluid to the turbine, a valve unit including a disc movable in the casing and coacting therewith to control the amount of said driving fluid supplied to the turbine, and means for controlling the movement of said disc including means responsive to the speed of rotation of said turbine, means having conduit connection to the discharge side of the pump, responsive to the pump discharge pressure and acting on said valve unit in opposition to the driving fluid pressure thereon, the latter said means including adjustable resilient means for varying the amount of opposition offered by said pump discharge pressure responsive means on said valve unit under any particular pump discharge pressure thereby to control the position of said disc in the valve casing.

19. Control mechanism for a turbine-driven pump, comprising a valve unit controlling the supply line to the turbine, means for applying to the valve unit the pressure prevailing on the delivery side of the valve unit in direction tending to close the supply line, means including a relatively small diameter conduit leading from the delivery side of an impeller of the pump to the region of the valve unit for applying to the valve unit the pressure prevailing at the delivery side of said impeller in direction tending to open the

supply line, and means in said relatively small conduit for varying the magnitude of the said supply-line-opening-tendency of the said delivery pressure as applied to said valve unit.

5 20. Control mechanism for a turbine-driven pump, comprising a valve unit in and controlling the supply line to the turbine, said valve unit including an inlet chamber in free communication with the supply line, and an outlet chamber in free communication with the turbine nozzle bowls, and including also valve means between said chambers for controlling flow therebetween, means in said valve unit for applying to said valve means the turbine nozzle bowl pressure in direction tending to close the supply line, means operatively associated with said valve means for applying the pressure of liquid on the delivery side of an impeller of the pump to the valve means in direction tending to open the supply line, and adjustable means acting with and in addition to the said pressure of liquid on said valve means in opposition to said turbine nozzle bowl pressure and having a normal condition of adjustment for maintaining said valve means slightly open even though the said pressure of liquid drops to zero.

15 21. Control mechanism for a turbine-driven pump comprising a valve unit having throttling means therein for controlling the supply line to the turbine, means for applying to the throttling means the turbine nozzle bowl pressure in direction tending to close the turbine supply line and for applying the pump delivery pressure to the throttling means in direction tending to open the turbine supply line, leverage mechanism in actuating relation to said throttling means and responsive to the pump delivery pressure for urging the throttling means in direction to open the supply line, and a spring associated with the leverage mechanism and acting on said throttling means through said leverage mechanism in the same direction as and in addition to the pump delivery pressure, said spring being adjustable to vary its effect on the throttling means.

22. Control mechanism for a turbine-driven pump comprising a valve unit having throttling means therein for controlling the supply line to the turbine, means for applying to the throttling means the turbine nozzle bowl pressure in direction tending to close the turbine supply line and for applying the pump delivery pressure to the throttling means in direction tending to open the turbine supply line, leverage mechanism in actuating relation to the throttling means and responsive to the pump delivery pressure for urging the throttling means in direction to open the supply line, said means for applying the pump delivery pressure to the throttling means including a relatively small conduit leading from the delivery side of the pump and applying the pump delivery pressure to said leverage mechanism, and valve means in said relatively small conduit for controlling said throttling means by controlling the relatively small flow of water under pump delivery pressure in said relatively small conduit.

45 23. Control mechanism for a turbine-driven pump comprising a valve unit having throttling means therein for controlling the supply line to the turbine, means on the throttling means and open to the turbine nozzle bowl pressure for applying to the throttling means the turbine nozzle bowl pressure in direction tending to close the turbine supply line, means operatively associated with the throttling means for applying the pump delivery pressure to the throttling means in direction tending to open the turbine supply line, said

means for applying the pump delivery pressure to the throttling means including a member arranged to act on said throttling means and a relatively small conduit leading from the delivery side of the pump and applying the pump delivery pressure to said member in direction tending to open the throttling means, and means in said relatively small conduit for varying the effect of the pump discharge pressure as applied to said member and thence to the throttling means.
